FUEL PUMP

Louis O. French, Milwaukee, Wis.

Application August 8, 1942, Serial No. 454,095

7 Claims. (Cl. 103—37)

The invention relates to fuel pumps.

The general object of the invention is to provide a fuel pump of the variable stroke type in which the pump plunger at less than full load returns before and independently of the return of its actuator. One special object of the present invention is to provide an improved form of variable stroke drive connection between the constant stroke actuator and the plunger. According to the present invention, I use a toggle linkage as a drive connection and a shiftable regulator to control the breaking of the toggle joint at different points in the stroke of the actuator to vary the stroke of the plunger. Thus while the knee of the toggle is free to be broken, there is no direct separation of the driving parts as in the structure shown and described in my copending application Serial No. 368,763, filed April 4, 1941, and the parts are thus subjected to less hard wear, and this wear is distributed over a greater surface area.

A further object of the invention is to provide a fuel pump having a variable stroke plunger with means for rotating the plunger to vary the time of the beginning of fuel injection.

The invention further consists in the several features hereinafter set forth and more particularly defined by claims at the conclusion hereof.

In the drawing:

Fig. 1 is a vertical sectional view through a fuel pump embodying the invention;

Fig. 2 is a detail vertical sectional view taken on the line 2—2 of Fig. 1;

Fig. 3 is a detail view of the operating linkage in an intermediate position;

Fig. 4 is a plan view of one of the links;

Fig. 5 is a detail view of the control member, parts being broken away;

Fig. 6 is a detail horizontal sectional view taken on the line 6—6 of Fig. 1;

Fig. 7 is a detail view, partly in section, of the drive connections between the controls.

Referring to the drawing, the numeral 10 designates a casing, 11 a pump barrel, 12 a plunger working in the barrel, 13 a discharge valve, 14 a spring for normally holding the valve 13 against its seat on the flanged seat member 15, 16 a clamping nut for member 15 and barrel 11 having threaded engagement with the upper threaded end of a bore 17 in the casing and bearing against a sealing gasket 18, 19 a spring interposed between the barrel and a flange 20 on the plunger and normally urging said plunger to a position in which its upper end uncovers an inlet port 21 in the barrel supplied with fuel from a mani-

fold 22 which is supplied from any suitable source of fuel supply connected to the threaded passage 23. During its delivery stroke the plunger 12 covers the inlet port 21 and forces the fuel in the barrel above the plunger past the spring loaded delivery or discharge valve 13 direct to a suitable injector if the device is of the so-called unit type or to piping supplying an injector mounted on the head or manifold of the engine or of the separate pump type.

The casing 10 is shown as formed of two parts secured together by screws 24, the upper carrying all the cylinders of a multi-cylinder pump and the lower the plunger operating mechanisms. As all of the pump units are the same, only one is shown in detail.

The lower casing section has a top wall 25, a back wall 26, base 27, and a partition 28 dividing this section into two compartments 29 and 30 whose fronts are covered by a removable plate 31. The top wall is apertured to receive a guide and plunger stop bushings 32 for each pump unit and the partition similarly apertured for tappet guide bushings 33. The bushings 32 are clamped between the two sections of the casing while the bushings 33 are secured to the partitions in any suitable manner as by hold down bolts 34 and washers 34', as shown in Fig. 6.

The plunger actuator comprises a tappet member 35 having a slidably splined or keyed connection 35' with the inner wall of the bushing 33 and carrying a rotatable roller 36 yieldingly held by a spring 37 against a cam 38 formed on the cam shaft 39 driven by the engine or in cyclic synchronism therewith. The tappet has a forked upper end 40.

A flanged tubular socket member 41 has a bore 42 in which lower end of the plunger 12 is loosely mounted and against which the spring 19 holds the flange 20 of the plunger in abutting engagement so as to act as a unit therewith. The flange 43 of the socket member abuts against the bushing 32 to limit the movement thereof, and the tubular portion of said member is slidably mounted in the bore of said bushing and has a forked lower end 44.

The forked end 44 of the member 41 is pivotally connected by a pin 44' with one end of a link 45 whose other end is pivotally connected by a pin 46 with the upper end of a link 47 whose lower end is pivotally connected by a pin 48 with the forked end 40 of the tappet member 35. The pin 46 may be formed integral with or connected to a roller 49 at one end and be in peened engagement with a roller 50 at its other end. The rollers

49 and 50 ride on the surface 51 of a rotatably shiftable stroke control member 52 which is mounted in the casing 10 for angular adjustment.

The links 45 and 47 are during the return stroke of the actuator 35 urged to swing toward the control 52 under the action of a cam surface 53 on the link 47 engageable with a cooperative surface in the form of a fixed rod 54, and this cam action, as the actuator 35 is moved by its spring 37 to its initial position brings the rollers 49 and 50 normally into contact with said control, and to further insure this engagement the control surface 51 is positioned so that the toggles are slightly out of line and biased toward said surface in the full stroke position of the parts as shown in Fig. 1. As the control member 52 is turned, its control surface changes its angularity relative to the rollers 49 and 50 with the result that as the actuator 35 is moved inwardly on its pumping stroke, the toggle formed by the links 45 and 47 will be bent to a position for breaking later or sooner in the stroke of the actuator depending upon the set position of the control surface 51, and when the break does occur, the spring 19 quickly returns the plunger 12 to its outer position independently of the actuator and of the speed of the engine. For "no load" the control surface 51 is set in the position shown in Fig. 3, and then during a very small part of the movement of the actuator 35 the knee of the toggle linkage is broken, and immediately the spring 19 brings the plunger and its associated member 41 back to the position shown in Fig. 3. Thereafter, the spring 37 returns the actuator 35 and with it the links 45 and 47 which will be swung back to their initial position by the engagement of the cam surface 53 with the rod 54 as the actuator reaches its initial position. In the no-load position the movement of the plunger 12, if any, under the action of the control 52 is so slight that it does not cover the inlet port 21, and consequently no fuel will be delivered past the discharge valve. Thus the changing of the angular position of the control member 52 changes the stroke of the plunger 12 and hence the amount of fuel furnished by the pump through the stroke of the tappet 35 is constant.

For a multi-cylinder pump the surface 51 for each pump unit is formed by notching the cylindrical shaft as shown in Fig. 5.

With stroke mechanism of the form above described, the stroke of the plunger starts with that of the actuator so that the time of beginning fuel injection is constant, and this has been found desirable on some engines. On other engines, particularly those of the direct injection type, it has been found advisable to delay the beginning of injection for part load charges of fuel, and during idling, over the time of injection of the full fuel charge and in the present instance means have been provided for this purpose comprising means for rotatably mounting the plunger 12, so that its obliquely inclined top or control edge 55 will change its position relative to the inlet port 21, so that said port will be closed sooner or later during the stroke of the plunger 12. For rotating the plunger I have mounted it for free rotation relative to its socket member 41 and have provided a slidably keyed or splined connection 56 between its flange 20 and a gear member 57 which is mounted in a

recess 58 in the casing 10 and is engaged by a rack 59 which reciprocates in a guide slot 60.

For a multi-cylinder engine the rack 59 engages the gear member 57 of each pump unit, 5 and to provide for a single operating control I have shown in Fig. 7 a gearing connection between the rack 59 and the control member 52 comprising a shaft 61 journalled in suitable bearings in an end plate 62 of the machine and 10 having a gear 63 meshing with said rack and a screw gear 64 meshing with its associated gear 65 on the control member 52, to turn said member through a relatively small angle to vary the stroke of the pump plungers 12 while turning the 15 plungers themselves to vary the commencement of the injection period, so that for full charge of fuel the injection may commence earlier in the cycle than for lighter charges. The control of the timing of the injection may be separately operated from the quantity control in some instances.

Pumps of the type above described have the advantage of simplicity of manufacture because only a plain cylindrical plunger and plain barrel are necessary, and this gives greater sealing surface than the scrolled relief plungers and a greater amount of time is available for the filling of the pump barrel because of the very quick return of the pump plunger by its return spring 20 to its inlet position before and independent of its actuator.

Where it is not necessary to vary the commencement of the injection period, the means for rotating the plunger 12 may be omitted in which 25 case the part 41 may be formed as an integral part of the pump plunger 12.

I desire it to be understood that this invention is not to be limited to any particular form or arrangement of parts except in so far as such 30 limitations are included in the claims.

What I claim as my invention is:

1. In a fuel pump having a barrel having an inlet port, a pump plunger reciprocating in said barrel and rotatable relative to said barrel, and 45 a spring for returning said plunger, the combination of an engine controlled reciprocatory actuator, a variable stroke drive connection between said actuator and said plunger to allow said plunger to be returned by said spring before and independently of said actuator, said plunger having an inclined control edge shiftable relative to said inlet port to control the beginning of fuel injection, and means for rotating said plunger.

2. In a fuel pump having a barrel provided with an inlet port, a pump plunger reciprocating in said barrel and rotatable relative thereto, and a spring for returning said plunger, the combination of an engine controlled reciprocatory actuator, a variable stroke drive connection between said actuator and said plunger to allow said plunger to be returned by said spring before and independently of said actuator, a shiftable control member for said variable stroke drive connection, said plunger having an inclined control edge shiftable relative to said inlet port to control the beginning of injection, means for rotating said plunger to shift said control edge, and means for simultaneously operating said plunger rotating means and said shiftable drive control member.

3. In a fuel pump having a barrel, a pump plunger reciprocating in said barrel and a spring for returning said plunger, the combination of an engine controlled reciprocatory actuator, a

breakable toggle joint drive connection between said actuator and said plunger, and adjustable means to control the breaking of the knee of said toggle joint to vary the stroke of said pump plunger.

4. In a fuel pump having a barrel, a pump plunger reciprocating in said barrel and a spring for returning said plunger, the combination of an engine controlled reciprocatory actuator, a shiftable control member, a breakable toggle joint drive connection between said actuator and said plunger having its knee normally biased toward said control member, said control member being operable on the knee of said toggle joint to control its release.

5. In a fuel pump having a barrel, a pump plunger reciprocating in said barrel and a spring for returning said plunger, the combination with an engine controlled reciprocatory actuator, a breakable toggle joint drive connection between said actuator and said plunger, adjustable stroke control means operable to break the knee of the toggle joint during the delivery stroke of said actuator, and cam means engageable with a link

of the toggle to reset the toggle joint during the return stroke of said actuator.

6. In a fuel pump having a barrel, a pump plunger reciprocating in said barrel, and a spring for returning said plunger, the combination of an engine controlled reciprocatory actuator, a releasable drive connection between said actuator and plunger, and a rotary shaft having a notch therein providing a control surface cooperating with said connection to control its release.

7. In a fuel pump having a barrel, a pump plunger reciprocating in said barrel and a spring for returning said plunger, the combination with an engine controlled reciprocatory actuator, a drive connection between said actuator and said plunger including a pair of toggle links, a rotatable stroke control member having a surface engaged by a part of the knee of said toggle links to break said knee during the delivery stroke of said actuator, one of said links having a cam surface and fixed means cooperating with said cam surface to reset the toggle joint during the return stroke of said actuator.
